UNITED STATES PATENT OFFICE

GEORGE HENRY, OF STEGE, CALIFORNIA

FOUNTAIN PEN

Application filed December 17, 1928. Serial No. 326,570.

My present invention relates to a fountain pen improvement and more particularly to means for starting the flow of ink.

An object of my invention is to provide a device suitable for use with fountain pens which is adapted to clean and start the flow of ink of a fountain pen in a clean and convenient manner.

Another object of my invention is to provide in combination with a fountain pen, means for cleaning the nib and starting the flow of ink without necessitating a shaking of the pen.

A further object of my invention is to provide in combination with a device of the above character, means which will act to compress the nib of the pen and the ink feeding device together and thus start the ink flowing.

The one serious objection to the use of fountain pens is the fact that where the pen is used infrequently, the ink very often dries upon the nib and thus interferes with the free flow of the ink when the pen is first picked up. A common practice under these conditions is to give the pen a violent shake so as to discharge ink out of the ink feeding device and upon the nib. This procedure is not only wasteful of the ink, but it also throws the ink about where it may cause damage to surrounding objects.

In order to overcome the above objections, I propose to provide a means which, when the nib of the pen is pushed thereinto, will clean the nib and start the flow of ink in a novel manner.

For a better understanding of my invention, reference should be had to the accompanying drawing, wherein

Figure 1 is a perspective view of my invention embodied in a desk weight showing a fragmentary portion of the pen adjacent thereto,

Figure 2 is a sectional view in elevation showing the manner of mounting the pen starting element shown in Figure 1, and

Figure 3 shows a preferred embodiment of my invention, partially in section, and applied to the cap of a fountain pen.

In Figures 1 and 2 of the drawing, 10 designates a block of material which may be

of any suitable substance, the only consideration being here that it possess some weight so that the complete device may then be used as a paper weight or the like. The member 10 is provided with a cylindrical opening 11 in the center thereof and a flared portion 12 at the upper end thereof. Mounted within the opening 11 I provide a plurality of vertically extending bristles 13 which are secured together at their ends by glue or other suitable means 14. Intermediate the ends of the bristles 13 I provide a resilient band 15 which acts to compress the bristles at substantially their central point. This member 15, owing to its resiliency, will, when a pen is forced into the bristles 13, yield and as a result create a corresponding pressure upon the nib and ink feeding member of the pen so as to squeeze them together and force ink out upon the nib.

In Figure 3 of the drawing I show my improved ink starter mounted upon the outer end of a fountain pen cap 16. The bristles 13 in this instance are mounted within a receptacle 17 in a manner similar to that previously described. The member 17 is mounted within the end of the cap so as to slide freely therein. A spring 18 is arranged within the cap 16 and acts against the member 17 to hold it in its outermost position and out of engagement with the nib of the pen which I here designate by the numeral 19. The arrangement and construction here shown is immaterial, the essential features being that the bristles 13 be located away from the nib and capable of being pressed thereover when desired. The nib 19 is shown as mounted upon a pen body 20 and having the usual ink feeding member 21 adjacent thereto.

The operation of my invention is as follows, assuming that it is desired to start the ink flowing in the pen 20. If the operator has a device such as is shown in Figure 1, he will merely project the nib of the pen into the bristles 13 and press downwardly thereupon. This will force the nib and its cooperating ink feeding member into the zone of the elastic member 15 and, as a result, the nib and ink feeding member will be pressed

together and ink forced out upon the nib. During this action, in addition to the above, the nib will also be cleaned.

When my device is incorporated in a fountain pen cap as is illustrated in Figure 3, the operator will merely by placing his thumb upon the member 17, force it inwardly and over the nib 19 before the cap is removed from the pen. This will press the nib and ink feeding device together as previously described and start the ink flowing.

The bristles 13 may be made up in independent units with the band 15 affixed thereto so that when the bristles become soiled, 15 dirty, and worn from use the whole may be removed bodily from its receptacle and quickly and easily replaced with a new and clean set of bristles.

While I have shown the preferred form 20 of my invention as now known to me, it is to be understood that various changes may be made in its construction without departing from the spirit of the invention as defined in the appended claims.

Having thus described my invention, what 25 I claim and desire to secure by Letters Patent is—

1. A fountain pen ink starter comprising a plurality of bristles arranged and secured 30 together at one end, and an elastic means about said bristles intermediate their ends tending to yieldingly press them tightly together, whereby when the pen nib and ink feeder are pushed therein pressure will be 35 exerted upon the nib and ink feeding member and ink forced out upon the nib.

2. A fountain pen starter comprising a receptacle, bristles arranged side by side and secured at one end into said receptacle, and 40 an elastic band about said bristles intermediate their ends for exerting pressure through said bristles upon the pen nib and ink feeder when pushed therein.

3. In a fountain pen cap, the combination 45 of a relatively movable receptacle in the end of said cap, bristles arranged within said receptacle, and means whereby said receptacle and bristles may be forced inwardly in said cap and over the nib enclosed by said cap, said 50 means normally operating to hold said bristles out of contact with the nib.

4. In a fountain pen cap, the combination 55 of a relatively movable receptacle in the end of said cap, bristles arranged within said receptacle, means whereby said receptacle and bristles may be forced inwardly in said cap and over the nib enclosed by said cap, and an elastic band about said bristles intermediate their ends adapted to exert pressure upon 60 said nib through said bristles when the nib is projected therein.

5. In a fountain pen cap, the combination 65 of a receptacle member reciprocatively mounted in the end of said cap, pen-wiping means carried by said receptacle member, and

means for returning said member and pen-wiping means to a retracted position after depression whereby they will be separated from said nib.

GEORGE HENRY.
